US00D939670S

(12) **United States Design Patent** (10) **Patent No.:** **US D939,670 S**
(45) **Date of Patent:** **** Dec. 28, 2021**

(54) **SHOWER HANDLE**

(71) Applicant: **Spectrum Brands, Inc.**, Middleton, WI
(US)

(72) Inventors: **Bingo Wang**, Xiamen (CN); **Andy Kim**, Lake Forest, CA (US)

(73) Assignee: **Spectrum Brands, Inc.**, Middleton, WI
(US)

(**) Term: **15 Years**

(21) Appl. No.: **29/736,936**

(22) Filed: **Jun. 4, 2020**

(51) LOC (13) Cl. **23-01**

(52) U.S. Cl.

USPC **D23/254**

(58) **Field of Classification Search**

USPC D23/238-243, 250, 524, 213;
D8/307-308, 353

See application file for complete search history.

(57) **CLAIM**

The ornamental design for a shower handle, as shown and described.

DESCRIPTION

FIG. 1 is a front perspective view of a shower handle showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines immediately adjacent to the photographic area define the bounds of the claimed design and form no part thereof. The unshaded areas within the broken lines form no part of the claimed design.

1 Claim, 7 Drawing Sheets
